BOX

Alwin W. D. Weis, Quincy, Ill., assignor to Central Fibre Products Company, Incorporated, Chicago, Ill., a corporation of Delaware

Application February 17, 1937, Serial No. 126,130

2 Claims. (Cl. 217—36)

This invention relates to boxes or crates generally referred to in the trade as Dozier style and made in substantial accordance with the disclosure of United States Letters Patent 609,879 issued August 30, 1898, to Dozier. The Dozier style box is extremely light in weight, it being made of various kinds of lightweight wood, such as cottonwood, and comprising single thickness veneer top, bottom and walls secured together by cleats. The Dozier style box has met with great acceptance in the box-making and box-using industries because of its comparative strength and lightness. For instance, it is extensively used in the shipment of dressed poultry because the freight rates for poultry are relatively high and the box is charged at the same rate as the poultry contents. Therefore, poultry shippers have found it desirable and economical to use a Dozier style box for their shipments. There are many other products which are shipped in the Dozier style box for the same and other reasons.

The Dozier style boxes as made heretofore have generally been constructed as already mentioned of single thickness veneer for the top, bottom and walls of the box, and cleats have been arranged along the edges of the walls with the cleats on the side walls overlapping the ends of the cleats on the end walls. Nails are driven through the overlapping ends of the side wall cleats. The nails are driven across the grain of the side wall cleats and into and parallel with the grain of the end wall cleats. The nails must be of sufficient size to securely hold the cleats together and generally it has been found necessary to use at least two nails in each end of each side wall cleat to satisfactorily secure it to its adjacent end wall cleat. The cleats, while much thicker than the veneer side walls, are nevertheless made as small as possible consistent with the desired strength. It has been found that driving the nails across the grain at the ends of the side wall cleats frequently splits the cleat along the grain to at least some extent, and to a very large extent the splits have been so great as to require the use of a third or auxiliary nail which has a still greater tendency to split the cleat because of there being two nails already present in adjacent relation thereto. Furthermore, it frequently happens that the split has been so great as to break off a piece of the cleat, rendering it useless and requiring replacement of the entire side of the box as the facilities for replacing only the cleat are generally not present in the field where the boxes are assembled. Such breakage occurs frequently especially where the cleat has been made from a long strip of wood having a knot therein adjacent or close to the line of severance of the cleat from the long piece of wood because the grain near the knot will not

be straight but will be curved to go around the knot. The assembler of the box is generally working at a high rate of speed and cannot take the time to discern how the grain runs at the point where he is driving the nail, especially because the wood used generally has a faint grain and close scrutiny is required to see it.

Because the nails are driven into the ends of the end wall cleats they are not secured therein as tightly as if it were possible to drive them across the grain and attempts have been made to coat the nails with a cement-like nail coating which will soften because of the heat developed in driving the nail and then set immediately to cause the nail to better hold in the end wall cleat. Use of coated nails has to some extent made a more tightly secured together box. However, the effect of the coating is largely lost due to its being scraped off of the nail when driving the nail across the grain of the side wall cleats and therefore little coating ever finds its way into the end wall cleats.

The nails securing the end wall and side wall cleats together have heretofore been positioned by hand and necessarily somewhat carelessly due to the speed with which the assemblers assemble the box and as a result the nails have frequently been located too close to the edge or end of the cleats, resulting in splitting thereof, or the nails have been located too close together and are therefore not as effective as they could be, and the nails have not been properly staggered to prevent alinement with the grain and consequent splitting of the end wall cleats. If the nails are driven into the end wall cleats in alinement with each other and with the grain of the end wall cleat, the two nails have the effect of wedging the grain apart frequently causing the end wall cleat to split. If more time were permitted the assemblers in driving the nails they could more accurately stagger them but in high speed assembling this has been impossible. If great care is not taken to drive the nails straight into the cleats, it frequently happens that the nails skew and protrude from the side of the end wall cleats and become a source of danger to a handler of the box.

The principal object of my invention is to more securely hold together the parts of a Dozier style box than has been done heretofore.

Another object of my invention is to construct the parts of a Dozier style box so that the parts may be assembled without damage thereto regardless of the direction or condition of the grain in the wood of the parts.

A further object of the invention is to provide a guide for the nails holding the parts of a Dozier style box together so that the nails will be driven straight and without skewing.

A still further object is to insure that when

coated nails are used the coating will stay on the pointed end of the nails until the nails have been driven home.

Other objects of the invention are to locate the position at which the nails securing the parts of a Dozier style box together are to be driven so that the nails will not be too close to the edge of the parts or to each other; to prelocate the place where the nails are to be driven so that they will be properly staggered and out of alignment and therefore decrease the possibility of splitting the box parts; and to provide a Dozier style box having an improved appearance due to the lack of splits, broken parts, protruding nails, etc.

Selected embodiments of my invention are illustrated in the accompanying drawing wherein

Fig. 1 is a perspective view of one corner of a box embodying my invention;

Fig. 2 is a detail sectional view on the line 2—2 of Fig. 1;

Fig. 3 is a detail view of one wall showing the cleats thereon in section; and

Fig. 4 is a detail enlarged sectional view illustrating the manner in which a nail holds two parts of the box together.

Referring to the drawing, a thin single thickness veneer side wall 5 of a Dozier style box has top and bottom cleats 6 secured thereto by usual wire staples 7. The cleats extend beyond the ends of the side walls a distance substantially equal to the thickness of the end wall cleats. The end walls 8 have cleats 9 fastened thereto by similar staples 7. The cleats 9 extend beyond the ends of the end walls 8 only sufficiently to engage the extending ends of the cleats 6. Holes 10 are drilled through the extending end portions of the cleats 6 to receive nails 11 which are adapted to secure the cleats 6 and 9 together. The holes 10 are slightly staggered so that they will not be in alignment with the grain of the cleats 9. The nails 11 may have a thin coating of a cement-like material and are of the type generally found in the commercial market having a coating which is adapted to melt slightly with the heat of friction developed during the driving of the nail. The holes 10 may be of a diameter approximately equal to the diameter of the outside surface of the coating on the nails or may be of slightly larger diameter as is illustrated for the purpose of clarity or may be even of slightly less diameter provided too much resistance will not result to the nail to scrape off the coating thereon.

The top 12 and bottom 13 of the box are constructed of a thin single thickness veneer having reenforce strips 14 stapled by staples 7 at strategic locations thereon. The reenforces are preferably located along the ends of the grain of the top and bottom and at other locations where found desirable to give added strength and to prevent warping. The top of the box may be removably secured to the walls by any suitable means such as the wire hinge and lock 15. The bottom of the box is secured to the side and end walls thereof by nails 16 extending through openings in the reenforce strips 14 and bottom 13 similar to the holes 10 in the side wall cleats. These nails may also be coated similar to the nails 11.

My invention provides that during the manufacture of the parts to be assembled to make a Dozier style box, the holes 10 may be drilled by machinery having predetermined drill locations so that the holes drilled thereby will be

straight, of the proper size, properly located, and properly staggered, whereby the box may be assembled without splitting of the parts due to driving the nails therethrough, without skewing the nails, and without scraping the coating off of the nails and, therefore, the box will be better appearing and more securely fastened together without damage to any of the parts.

While I have illustrated and described selected embodiments of my invention it is to be understood that these are capable of variation and modification and I therefore do not wish to be limited to the precise details set forth but desire to avail myself of such changes and alterations as fall within the scope of the following claims:

I claim:

1. A Dozier style box including preformed top, bottom, side and end wall units for assembly at the point of use, the preformed side and end wall units being in sets and including cleats fixed horizontally of the units, the cleats on one set of said walls extending beyond the ends thereof whereby the cleats on said one set of said walls when assembled overlap the ends of the cleats on the other set of said walls, said overlapping cleats having staggered nail guide openings therethrough in the extended ends thereof, and cement coated, headed nails extending through said openings with the coated ends thereof embedded in the ends of said overlapped cleats and the heads thereof substantially flush with the outer surface of said overlapping cleats at the openings therethrough, said openings being of a diameter approximately equal to the diameter of the outer surface of said coating and of less diameter than the diameter of the heads of the nails whereby when said coated nails are inserted into said openings and driven into the overlapped cleats they will be effectively guided straight into staggered points of the overlapped cleats and the coating on the ends of the nails will enter the overlapped cleats cementing the ends of the nails therein and without the coating being scraped off the ends of the nails by the overlapping cleats.

2. A Dozier style box including preformed top, bottom, side and end wall units for assembly at the point of use, the preformed side and end wall units being in sets and including cleats fixed horizontally of the units, the cleats on one set of said wall units extending beyond the ends thereof whereby the cleats on said one set of said wall units, when assembled, overlap the ends of the cleats on the other set of said wall units, said overlapping cleats having openings therethrough in the said extended ends thereof, and cement coated, headed nails extending through said openings with the coated ends thereof embedded in the ends of said overlapped cleats and the heads thereof substantially flush with the outer surface of said overlapping cleats at the openings therethrough, said openings being of a diameter approximately equal to the diameter of the outer surface of said coating and of less diameter than the diameter of the heads of the nails whereby when said coated nails are inserted into said openings and driven in guided relation therethrough into the overlapped cleats the coating on the ends of the nails will enter the overlapped cleats for cementing the ends of the nails therein and without the coating being scraped off the ends of the nails by the overlapping cleats.
